SAFETY RAZOR

Filed July 2, 1935

UNITED STATES PATENT OFFICE

2,031,223

SAFETY RAZOR

Joseph F. Mellen, Providence, R. I.

Application July 2, 1935, Serial No. 29,489

2 Claims. (Cl. 30—44)

My invention relates to that type of safety razor, or mount for a safety razor blade, wherein reciprocatory motion is imparted to the blade transversely of the direction of the drawing movement.

Certain objects of my invention are to generally facilitate and speed the severance of the beard from the flesh, and to prevent blade cuts, and skin scraping.

10 Further objects are to provide in a blade carrier the functions of both a container and a clamp; to facilitate the insertion and removal of the blade therefrom; and to effect these results in an inexpensive and compact structure having a minimum of parts.

Additional objects are to actuate the slidable carrier by a direct and positive means, thereby avoiding the friction incident to the presence of interposed gears, cams, worms, or other rotary elements, and to enable the actuating of the carrier to be initiated by a natural and effortless movement of the operator.

Other objects and advantages will be herein-after pointed out.

25 To all of the above ends essentially my invention consists in such parts and in such combinations of parts as fall within the scope of the appended claims.

In the accompanying drawing which forms a part of this specification.

Figures 1 and 2 are a side elevation and a top plan view respectively of a safety razor embodying my invention.

Figures 3, 4, and 5, sections of the same taken respectively on line 3-3 of Figure 2, and lines 4-4 and 5-5 of Figure 3,

Figure 6, a perspective view of the blade carrier in open position.

Figure 7, a fragmentary section taken on line 40 7-1 of Figure 3,

Figure 8, a detail perspective view of the op-

erating lever, and
Figure 9, a similar view of the bushing and
spring.

45 Like reference characters indicate like parts throughout the views.

My device comprises a sectional tubular handle 13 fixed to or integral with which is a yoke

50 shaped attaching plate 15. In this instance a plug 16 fast in the handle is riveted, as at 19, to the head portion of the plate. Lugs 21 upon the arm portions of the plate are soldered or otherwise fixed to a transversely curved comb plate 23, provided in its top face with a central longitudinal guideway 25 defined by marginal shoulders 55

26 adjacent the teeth 27 of the plate. A central rectangular opening 29 in the center of plate 23 merges in intermediate portions of interspaced longitudinal slots 30, as shown in Figure 5.

A blade carrier 32, as shown in Figure 6, comprises a blade plate 33 and a clamping plate 34 connected at their adjacent ends by a hinge member 35. The second plate, composed of thin resilient material, is provided at its free end with a perforation 38 to admit a resilient thumb catch 39 upon the first plate including a shoulder 40 to engage the second plate. The carrier plates 33 and 34 are both transversely curved but, as shown in Figure 4, the arc radius of the upper plate 34 is less than that of the lower plate 33 whereby the gripping power of the former upon a double edged razor blade 42 of usual construction interposed between the plates is increased. 10 15

The blade plate 33 is slidable in the guideway 25 with its upper face substantially flush with the adjacent surface of the plate 23. Two interspaced hook shaped attaching or guide lugs 43, formed upon each lateral margin of the plate 33, depend through the slots 30 and underlap the plate 23 which they slidably engage. Interspaced blade studs 44 longitudinally disposed upon the plate 33 centrally thereof are adapted to pass through the receiving holes 45 of the blade 42.

When it is desired to insert or substitute a blade in the carrier 32 the catch 39 is outwardly pressed to release the plate 34 which is then swung open to give access to the plate 33.

For imparting reciprocatory movement to the blade carrier 32 a split bushing 46 is fixed by friction or otherwise in an intermediate portion of the handle 13 and is provided with a vertical slot 47 to receive an upright flat spring 48. Above the latter is journaled in diametrically opposite openings 50 in the handle a transversely plano convex rock shaft 51 to the ends of which are fixed the legs 53 of a yoke lever 54 whose head 55 is provided with a slot 56 adapted to slidably receive a depending pin 57 fixed in the center of the blade plate 33. The lever 54 bridges the longitudinally disposed attaching plate 15. 59 represents washers interposed between the legs of the yoke lever and the handle.

A finger lever 61 comprises a shank 62 terminating in parallel offset ears 63 integral with its upper end provided with openings 65 through which the shaft 51 passes, the shapes of the openings conforming to the transverse shape of the shaft to which the lever 61 is operatively fixed. The shank 62 of the lever is normally downwardly and slightly outwardly inclined and extends 55

- through a vertical slot 67 in the handle. Adjacent the ears, and in this instance integral therewith, are angular abutment projections 69 adapted to normally rest against the spring 48.
- 5 To utilize my device the operator grasps the handle 13 with the end of his advanced forefinger engaging the outer face of the lever portion 62. By contracting the forefinger the lever is moved to its broken line position, shown in 10 Figure 5, whereby, through the yoke lever, the carrier 32 is moved to the end of its travel in one direction. Thereupon the forefinger is relaxed and the spring 48 returns the carrier to the limit of its travel in the opposite direction. The quick 15 vibration of the forefinger is continued during the period of drawing the razor blade over the face, with the result that the beard cutting is rendered more effective and speedy, and tearing, cutting or other injury to the skin avoided.
- 20 By use of the yoke lever 54 a more extended throw of the carrier is possible than by the use of a lever bar which from necessity would require mounting within the handle where the extent of swing is limited.
- 25 The fixed relation of both the finger lever 61 and yoke lever 54 with the rocking element 51 produces a positive and direct driving action to the carrier, and avoids the added friction caused

by more complicated mechanical combinations.

The hinged relation of the constituent plates of the carrier make repeated relative adjustment of the plates unnecessary, insures against accidental loss of either of the latter, and facilitates the insertion and clamping of the blade.

I claim:—

1. In a safety razor, a handle, a plate above the handle provided with an opening, an attaching plate fixed intermediate its lengths to the end of 10 the handle and fixed at its ends to the first plate at opposite sides of the opening, a blade carrier slidably mounted on the first plate over the opening, a rock shaft journaled in the handle, a yoke lever fixed to the shaft and bridging the attaching 15 plate pivotally connected with the carrier through the opening, and an operating lever fixed to the shaft.
2. In a safety razor, a handle, a comb plate supported by the handle provided with interspaced 20 longitudinal slots and with a central opening, a blade carrier slidably mounted upon the comb plate, lugs upon the carrier engaging the comb plate through the slots, a shaft journaled in the handle, and a lever upon the rock shaft pivotally 25 connected to the carrier through the opening.

JOSEPH F. MELLEN.
